**LIQUID FLOW CONTROL VALVE FOR
TOILET FLUSH TANKS**

Louis Sirotek, 1711 N. Nashville Ave., Chicago, Ill.
Filed Nov. 19, 1963, Ser. No. 324,771
4 Claims. (Cl. 137—218)

This invention relates to improvements in liquid flow control valves, particularly, to that type of valve employed in toilet flush tanks for automatically controlling the filling thereof with water to a predetermined level, and the discharge of water therefrom, as and when actuated.

What may be stated to be a principal object of the invention is the provision of a valve of the stated character which is of compact construction and small size, embodying only a minimum of parts, each of which is of durable and lasting form, operationally dependable and capable of being easily and quickly assembled; moreover, likewise disassembled for inspection, repair, replacement or cleaning.

An equally important object of the invention is to provide a liquid or water flow control valve which, when actuated to permit discharge of water therethrough and therefrom, will assure a complete and effective discharge of such from a toilet flush tank equipped therewith, hence, a thorough flushing operation, and by the same token, will function automatically to permit replenishment of said tank with a predetermined amount of water for future flushing usage.

Another object of the invention is to provide a valve of the stated kind which, in usage, will prevent undesirable back siphonage of water therethrough into the provided water supply line, thus eliminating the hazard of contamination.

A further object of the invention resides in the provision of a water flow control valve for toilet flush tanks which will be substantially noiseless in operation, will eliminate the cascading and swirling of water when discharged therefrom into an equipped tank, and as importantly, will be instantly positive in its water flow shut-off operational phase, thereby, will eliminate water whistling or similar noise experienced, without exception, in now prevalent types of valves wherein or whereby the shut-off of water inflow to a tank is effected gradually.

A still further object of the invention is to provide a toilet flush tank valve of such construction as will permit the selective modulation of water outflow therefrom, whereby to prevent possible flooding of an equipped tank by water discharged thereto at a rate faster than the capacity of the tank overflow pipe to drain the same off through a toilet bowl; particularly, in those cases where the pressure of the water supply is high and/or variable; additionally, to provide for less restrictive outflow in instances where the pressure of the water supply is lower, hence, assuring adequate and rapid filling of said equipped tank.

Yet another object of the invention is to provide a flush tank valve which, should the water passage ways of active or working components thereof become clogged or obstructed, they may be conveniently and quickly cleaned or cleared without the necessity of a complete disassembly and reassembly task.

The foregoing, as well as other objects, advantages and meritorious teachings of my invention will be in part obvious and in part pointed out in the following detailed

2

disclosure thereof, when taken in conjunction with the accompanying drawings, it being understood that the form of the invention presented herein is precise and what is now considered to be the best mode of embodying its principles, but that other modifications and changes may be made in specific embodiments without departing from its essential features.

In the drawings:

FIGURE 1 is a longitudinal section through a water flow control valve constructed in accordance with my invention, taken on the line 1—1 of FIGURE 2, looking in the direction in which the arrows point.

FIGURE 2 is a transverse section taken on the line 2—2 of FIGURE 1, looking in the direction in which the arrows point.

FIGURE 3 is a longitudinal section similar to FIGURE 1, with the lower portions of the water inflow and discharge pipes broken away, but wherein the working parts of the valve are shown in their closed positions or 20 relationships, as when an equipped flush tank has been filed with a predetermined amount of water.

FIGURE 4 is a transverse section taken on the line 4—4 of FIGURE 1, looking in the direction in which the arrows point, and,

25 FIGURE 5 is a like section taken on the line 5—5 of FIGURE 3, looking in the direction in which the arrows point.

Referring in detail to the drawings, the invention comprises a casing including lower and upper opposed circular shaped and dished sections 1 and 2, respectively, formed with complementary and alignable apertured ears 3 receiving screws 4 whereby the sections will be fluid tightly interconnected and form a chamber therebetween.

The lower section 1 is formed or otherwise provided 35 with a downwardly and coaxially extended sleeve 5, and with a series of perforations or ports 6 outwardly of and about the sleeve. A seating washer 7 is received flushly in the rabbeted upper end of the sleeve serving to increase its diaphragm seating area.

40 As shown in FIGURES 1 and 3 of the drawings, an intermediate portion of the sleeve is thickened and formed with a plurality of longitudinally and circularly disposed ducts 8, while a coaxially disposed nipple-like part or tube 9 is integral with and extends upwardly 45 through the seating washer 7 from and above the sleeve into the aforesaid casing chamber, its open upper end forming a valve seat, and its lower end forming an annular shoulder 7' in said thickened intermediate portion, the purpose of which is hereinafter described.

50 The upper section 2, constituting a cover for the lower section 1, is formed with an outwardly extending and opening nipple 10 and an upright post 11 to or on which a suitable type of float carrying arm 12 is pivotally mounted, as at 13.

55 The float arm consists of a fitting 14 sleeved on one side to threadedly receive a rod 15 of appropriate length, the outer end of which mounts a usual ball or other type of float, not shown. The opposite side of the fitting is formed or otherwise provided with a downwardly opening cap 16 having a gasket 17 seated therein. Said cap is so positioned and is of such diameter that when pivoted downwardly, it will have capping and closing engagement over and with the outwardly opening nipple 10.

Diaphragms 18 and 19, each made of durable and 60 tough flexible temporary deformable material, are snugly received within the casing chamber in superimposed relation, the diaphragm 18 being lowermost. The dia-

phragm 18 has a concentrically located opening of diameter greater than that of the nipple-like part 9 therein and receives the same therethrough, while the upper diaphragm 19 concentrically and fixedly receives an eyelet 20 having an inwardly tapered way therethrough, the lower end of which is of a shape and size receivable, at times, in the adjacent open end of the nipple-like part 9.

Fixedly positioned between the diaphragms 18 and 19 and spanning the casing chamber is an inflexible dished perforate disk 21, the medial portion of which snugly receives the upper end of the nipple-like part 9 therethrough.

The valve assembly, as above described, is mounted on the upper end of a liquid (water) supply stand pipe 22, the upper end of which is engaged and secured in the aforesaid thickened intermediate portion of the sleeve 5 in proximity to its annular shoulder 7', as shown in FIGURES 1 and 3 of the drawings, its lower end being provided with a suitable fitting 23 for connecting it to the bottom of a flush tank and to a supply source, not shown.

A liquid (water) discharge pipe 24 is received over the stand pipe 22 in spaced relation thereto forming a channel therebetween, having its upper end screw threadedly engaged in the lower open end of the sleeve 5 and adjustable toward or away from the shoulder 7' and the longitudinally disposed ducts 8. The length of said discharge pipe is less than that of the stand pipe, permitting the downward discharge of liquid (water) into the equipped flush tank, for an obvious purpose.

At this point, it is noted that by rotating or turning the discharge pipe 24 in one of two directions, the distance from or relating of its upper end with respect to the aforesaid shoulder 7' and the ducts 8 will be either increased or decreased. Because the channel between it and the stand pipe is offset from the ducts 8, the flow of liquid (water) from the valve via said ducts may be regulated to the required nicety. Thus, should the service pressure of a water supply be high, its flow can be suitably regulated by decreasing the distance between the discharge pipe end and said ducts 8. Conversely, if the service pressure of water is low, the discharge pipe is rotated in a reverse direction, increasing the distance between it and the ducts, consequently, offering less impedance to its flow. Thereby, the discharge of liquid (water) will be modulated to an extent as will eliminate excessive turbulence thereof, especially when it is delivered or flowed into a toilet bowl.

As and when the valve is employed in connection with a toilet flush tank, a refill tube 25, of appropriate diameter, is tapped into the sleeve 5 and serves to provide liquid (water) to a toilet bowl communicating therewith via the usual flush tank overflow pipe, not shown, this to provide a sewer gas seal thereto.

In operation of my improved valve, assuming that it is installed in a toilet flush tank and connected to a water supply source, when the tank is empty and the float carrying arm is in its lowermost position, the cap 16 will be raised and disengaged from the nipple 10 on the upper casing section 2. Water will be discharged from the stand pipe 22 into the area (chamber) between the diaphragms 18 and 19. A portion of the water will be outletted through the nipple 10 via the inwardly tapered opening in and through the eyelet 20. Furthermore, the pressure of the outflowing water will be sufficient to flex the lower diaphragm 18 downwardly, thus, sealing the multiple vent ports, and the upper diaphragm 19 upwardly to the positions shown in FIGURE 1 of the drawings. Such flow of water will continue through the perforations of the inflexible disk 21, through the opening between the nipple-like part 9 and the depressed flexible diaphragm 18 downwardly through the ducts 8 into and through the channel between the stand pipe 22 and the discharge pipe 24, ultimately discharging into the equipped flush tank.

As hereinbefore stated, by adjusting the spacing be-

tween the upper end of the discharge pipe 24, the rabbeted portion or shoulder 7' and the ducts 8, the pressure of the water discharged into the flush tank will be so regulated as to prevent excessive turbulence thereof, and too rapid filling of the tank.

As and when the float carrying arm is moved to its uppermost position, as shown in FIGURE 3 of the drawings, i.e., the level of water within the flush tank has reached the desired height, the cap 16 on the float arm fitting 14 will be engaged over and will close the nipple 10. The nipple being thus closed, will prevent further discharge of water therefrom, resulting in a build up of water and pressure within that portion of the casing chamber between the upper diaphragm 19 and the casing section 2 to an extent which will effect downward flexing of said diaphragm 19 and engaging it with and over the adjacent open end of the nipple-like part 9. Concurrently, the inherent resilience or spring of the lower diaphragm will be such that, being relieved of pressure from outletting water, it will flex or move upwardly into contact with the inflexible disk 21, closing the perforations therein. Thereby, backflow or discharge of water from the tank will be positively prevented.

With flexing movement of the lower diaphragm 18 upwardly to its cut-off position, as shown in FIGURE 3 of the drawings, the ports 6 in the lower casing section 1 outwardly of the sleeve 5 will be opened. Thereby, a positive venting action will be effected in order to break any suction which may have occurred in the water discharge channel between the stand pipe 22 and the discharge pipe 24, hence, prevent any and all contaminating back flow of water into the water supply stand pipe 22.

As and when a flush tank equipped with my improved valve is operated to effect discharge of water therefrom for a flushing operation, the float carrying arm 15 will descend with the lowering water level, causing the fitting provided cap 16 to be disengaged or removed from the nipple 10 and thereby allow the discharge of water from the supply stand pipe 22 into the casing chamber between the lower and upper diaphragms 18 and 19, hence repeating the water inflowing action through the valve, as hereinabove described.

Should, for any reason, the inwardly tapering channel in or through the eyelet 20 become clogged, it will be seen that it may be conveniently and easily cleared by removing the fitting 14 of the float carrying arm 12 from its mounting on the post 11, whereupon, a pin, wire or other device can be inserted and moved downwardly through the nipple 10 and said inwardly tapered opening in the eyelet 20, hence, clearing the latter.

The few and durable parts of my improved valve assure its long service with a minimum of maintenance requirement. Moreover, the valve will function to effect a positive shut-off of liquid flow therethrough or therefrom at a predetermined point of its operation in that the pressure of the flowed liquid is employed for the accomplishment; furthermore, that the greater the flow pressure of such liquid, the greater will be the character of the shut-off.

The aforesaid few and durable working parts of the valve, including the diaphragms 18 and 19, each made of flexible temporary deformable material, further assure its long service.

Excessive turbulence of liquid discharged via the valve into a toilet tank will be prevented by adequate adjustment of the discharge pipe 24 with relation to the ducts 8 in the sleeve 5 whereby to effect and maintain a uniform and satisfactory modulated rate of flow thereof.

The liquid shut-off action of the diaphragms 18 and 19, furthermore, will eliminate so-called "hammer" and similar noise.

And, as stated hereinbefore, cleaning of the working components of the valve is conveniently and easily effectable, this without a major disassembling thereof.

Because of the solid backing or support provided to the

diaphragms 18 and 19, it will be understood and appreciated that when the same is flexed upwardly, as hereinbefore described, distortion or rupture thereof will be prevented, hence, according greater longevity of dependable and satisfactory functioning of the same.

I have found it desirable to position a spacing washer 21' between the perimeter portions of the diaphragm 18 and the inflexible disk 21 whereby to effect a satisfactory area or water way as between the same when water is discharged into the valve casing and courses through the perforations of said inflexible disk to and through said diaphragm 18 and thence into and through the ducts 8 for downward discharge into an equipped flush tank. Obviously, by increasing or decreasing the thickness of this washer 21', greater or lesser water flow way area may be optionally effected.

It is to be understood that whereas I have herein described my invention for use in connection with a toilet flush tank, and as being advantageous for such use, it is not my intent to be limited thereto. Obviously, the invention has other and equally advantageous uses.

I claim:

1. A liquid flow control valve for flush tanks, comprising:
  - (a) a casing,
  - (b) a sleeve extended outwardly and downwardly from the lower side of the casing, a portion of which is thickened and formed with ducts extended longitudinally therethrough and communicating with the casing interior,
  - (c) fluid pressure actuated liquid flow control valve means within the casing,
  - (d) a liquid supply pipe connected to and communicating with the casing interior, and
  - (e) a liquid discharge pipe engaged over and above the supply pipe connected to said sleeve for movement toward and away from its thickened portion and ducts whereby to regulate the flow of liquid thereinto and therefrom.

2. A liquid flow control valve for flush tanks, 40 comprising:

- (a) a casing having a downwardly extended and opening sleeve communicating with its interior,
- (b) a portion of said sleeve being internally thickened and having longitudinally disposed ducts formed in and extended therethrough,
- (c) a longitudinally disposed tube within the sleeve inwardly of said ducts and extended into the casing interior,
- (d) the lower side of the casing being vented outwardly of the sleeve,
- (e) liquid pressure actuatable valve means within the casing one of which is seatable, at times, over the extended end of said tube and is formed with a medially located port, and another of which receives said extended end of the tube therethrough and is seatable, at times, over the vents in the lower side of the casing,
- (f) an outwardly opening nipple on the upper side of the casing communicating with its interior, 60
- (g) a float carried arm pivotally mounted on the casing upper side,
- (h) means carried by said arm engageable, at times, over said nipple whereby to close the same,
- (i) a liquid supply pipe connected to and communicating with said tube, and,
- (j) a liquid discharge pipe engaged over and about the supply pipe adjustably connected at its upper end to the lower end of said sleeve for movement toward or away from its thickened portion and ducts whereby to regulate the flow of liquid from said ducts thereinto and therefrom.

3. A liquid flow control valve for flush tanks, comprising:

- (a) a casing including upper and lower sections forming a chamber therebetween when joined,
  - (b) the lower section having a sleeve extending outwardly therefrom and communicating with the chamber and a plurality of vent openings therein outwardly of the sleeve,
  - (c) a portion of said sleeve being internally thickened and having a plurality of longitudinally disposed ducts formed in and extended therethrough,
  - (d) a coaxially disposed nipple-like part fixedly carried within the sleeve inwardly of said internally thickened portion thereof and extended into the casing chamber,
  - (e) a perforate non-flexible piece carried within the casing spanning the chamber and receiving the extended and adjacent end of the nipple-like part therethrough,
  - (f) an inherently spring flexible diaphragm secured within the casing in proximity to and below said perforate piece spanning the chamber and receiving the extended end of the nipple-like part therethrough,
  - (g) a flexible second diaphragm secured within the casing in proximity to and above the perforate piece spanning the chamber and having a medially located port therethrough,
  - (h) an outwardly disposed nipple on the casing upper section communicating with the chamber,
  - (i) a float carrying arm pivotally mounted on said casing upper section,
  - (j) a cap-like member carried by said arm engageable, at times, over the outer end of said nipple whereby to close the same,
  - (k) a liquid supply pipe connected to and communicating with said nipple-like part, and,
  - (l) a liquid discharge pipe engaged over and about the supply pipe adjustably connected at its upper end to the lower end of said sleeve for movement toward or away from its internally thickened portion and ducts whereby to regulate the flow of liquid from said ducts thereinto and therefrom.
4. A liquid flow control valve for flush tanks, comprising:
    - (a) a casing including upper and lower sections forming a chamber therebetween when joined,
    - (b) the lower section having a sleeve extending outwardly therefrom and communicating with the chamber and a plurality of vent openings therein outwardly of the sleeve,
    - (c) a portion of said sleeve being internally thickened and having a plurality of longitudinally disposed ducts formed in and extended therethrough,
    - (d) a coaxially disposed nipple-like part fixedly carried within the sleeve inwardly of said internally thickened portion thereof and extended into the casing chamber,
    - (e) a perforate non-flexible piece carried within the casing spanning the chamber and receiving the extended and adjacent end of the nipple-like part therethrough,
    - (f) an inherently spring flexible diaphragm secured within the casing in proximity to and below said perforate piece spanning the chamber and receiving the extended end of the nipple-like part therethrough,
    - (g) a spacing washer positioned between the perimeter portions of said perforate nonflexible piece and said inherently spring flexible diaphragm,
    - (h) a flexible second diaphragm secured within the casing in proximity to and above the perforate piece spanning the chamber and having a medially located port therethrough,
    - (i) an outwardly disposed nipple on the casing upper section communicating with the chamber,
    - (j) a float carrying arm pivotally mounted on said casing upper section,

- (k) a cap-like member carried by said arm engageable, at times, over the outer end of said nipple whereby to close the same,
- (l) a liquid supply pipe connected to and communicating with said nipple-like part, and,
- (m) a liquid discharge pipe engaged over and about the supply pipe adjustably connected at its upper end to the lower end of said sleeve for movement toward or away from its internally thickened portion and ducts whereby to regulate the flow of liquid from said ducts thereinto and therefrom.
